ULTRA HIGH FREQUENCY ANTENNA

Robert G. Schriefer, Fort Wayne, Ind., assignor,
by mesne assignments, to Farnsworth Research
Corporation, a corporation of Indiana

Application April 28, 1947, Serial No. 744,435

6 Claims. (Cl. 250—33)

1

This invention relates to antennae and particularly to an ultra-high frequency vertical antenna adapted for use in mobile communications.

For railroad radio communications an antenna is required which has a low clearance. The space limitations imposed on a railroad antenna require that the antenna be mounted in close proximity to the metallic vehicle body which may cause distortion of the radiation pattern, and may reduce the field strength due to the absorption of a portion of the radiant energy by adjacent metallic surfaces.

Furthermore, it has usually been required in antenna installations to provide an impedance matching device for the purpose of obtaining an efficient energy transfer between the radiating element and the antenna feeder line. Alternatively, the length of the antenna may be varied until the desired resistive component is obtained, whereupon the reactive component may be tuned out. These conventional arrangements necessarily complicate the installation and adjustment of the antenna and often cause inefficient operation due to the instability, or mechanical slippage of the tuning or impedance matching components. Further deficiencies of the prior art antennae reside in the lack of adequate weatherproofing for the protection of the antenna and its feeder line and the absence of sufficient mechanical ruggedness required to withstand the severe vibration and shocks to which a mobile antenna is subjected.

It is, therefore, an object of the present invention to provide an ultra-high frequency antenna especially adapted for use in mobile radio communication services in view of its low vertical dimensions.

Another object of the invention is to provide a self-supporting antenna of great mechanical strength having structural simplicity and wherein the elements are dimensioned so as to provide a resonant structure having a predetermined input impedance for matching the antenna impedance to that of the antenna feeder line.

A further object of the invention is to provide an antenna structure devoid of insulation and substantially impervious to accumulations of snow, ice or sleet, and which furthermore provides a weatherproof housing for the connecting elements contained within the antenna structure.

In accordance with the present invention there is provided an antenna comprising a coaxial transmission line having an inner conductor and

2

an outer conductor. A cylindrical member is provided which has a diameter different from that of the outer conductor, that is, it may be larger than the outer conductor. This cylindrical member extends beyond the transmission line. Means are provided for connecting the inner conductor to an extremity of the member and further means are provided for mechanically supporting the cylindrical member.

10 For a better understanding of the invention, together with other and further objects thereof, reference is made to the following description, taken in connection with the accompanying drawing, and its scope will be pointed out in the appended claims.

In the drawing, the single figure is a cross sectional view of a vertical antenna embodying the present invention.

Referring now to the drawing, there is illustrated a coaxial vertical antenna comprising outer cylinder 10 and inner cylinder 11. The upper rim of outer cylinder 10 is affixed to a metallic plug 12 which is, for example, screwed upon the upper rim of the inner cylinder 11. The outer cylinder 10 extends downwardly, in skirt fashion, concentrically with a substantial portion of the upper length of inner cylinder 11. The inner cylinder 11 serves as a support for the antenna structure and is mounted on base plate 15 and may be fixed thereto by set screw 18. The base plate 15 is then fastened to a ground plane or metallic surface 16 by the mounting screws 17. Metallic surface 16 is preferably grounded, as shown, thereby to maintain the cylinders 11 and 10 at direct current ground potential.

By this arrangement, a rigid and self-supporting metallic antenna structure is provided, wherein no insulation is required, and wherein the entire antenna structure may be maintained at a direct current ground potential.

40 There is provided a coaxial transmission line comprising the lower section of inner cylinder 11 and the center conductor 20 which serve as an antenna feeder line for supplying alternating excitation current to the antenna or for feeding alternating current from the antenna to a receiver. Aperture 21 is arranged in the sidewall of inner cylinder 11, and the free end of the center conductor 20 extends through this aperture and is electrically connected to the lowermost portion of outer cylinder 10, that is, to its lower extremity.

45 The electrical length of the antenna extending above metallic surface 16 corresponds to one quarter of the operating wave length as indi-

cated in the drawing. L_1 indicates the length of outer cylinder 10, while L_2 is the length of the exposed portion of inner cylinder 11, that is, the portion of inner cylinder 11 which is not surrounded by outer cylinder 10 and which extends beyond metallic surface 16. D_1 and D_2 indicate the diameter of the outer cylinder 10 and of the inner cylinder 11, respectively.

The inductive and capacitive reactive components and the radiation resistance of the coaxial antenna of the invention are mainly dependent upon the ratios of the lengths L_1 , L_2 and of the diameters D_1 , D_2 .

The antenna of the invention is substantially equivalent to a vertical quarter wave dipole and accordingly will have an omnidirectional horizontal radiation pattern and will radiate a vertically polarized wave. A high frequency excitation current applied to the antenna through the coaxial feeder line 11, 20 will excite the outer surfaces of inner cylinder 11 and of outer cylinder 10 which together form a resonant structure thereby to establish an omnidirectional horizontal radiation field about the antenna.

When the antenna is excited, high frequency currents will be present on the outer surface of outer cylinder 10 as well as upon the outer surface of the exposed portion of inner cylinder 11. These currents must be in phase and are indicated for a given instant by arrows 22 and 23. At the same time the high frequency currents flow through coaxial transmission line 11, 20. Thus, a current indicated by arrow 24 flows along the outer surface of inner conductor 20 in the same direction as the current flowing on the outer surfaces of cylinders 10 and 11. Since the exposed portion of inner cylinder 11 forms part of the coaxial transmission line, a current indicated by arrow 25 will flow on the inner surface of cylinder 11 in the opposite direction from that flowing on its outer surface and indicated by arrow 23. The currents distributed over the combined outer conducting surfaces of cylinders 11 and 10 as indicated by arrows 22 and 23 for a certain instant cause the structure to resonate and to function as an antenna. It is to be understood that the currents represented by arrows 22 to 25 will flow in the reverse direction during the opposite portion of a cycle of operation.

The portion of cylinder 11 arranged within outer cylinder 10 is not important for the operation of the antenna but mainly serves as a support for the outer cylinder 10. However, the electrical connection established from the metallic surface 16 through inner cylinder 11, metallic plug 12 to outer cylinder 10 keeps the entire antenna structure at a direct current ground potential.

Experiments have revealed that when the entire physical length of the antenna extending beyond metallic surface 16 is kept constant, while the length L_1 of outer cylinder 10 is reduced, which simultaneously will increase the length L_2 of the exposed portion of inner cylinder 11, the antenna resonates at a slightly higher frequency while the antenna input impedance is simultaneously increased. Inversely, if the length L_1 is increased while the length L_2 is decreased and the total length of the antenna maintained constant, the antenna will assume a slightly lower resonant frequency and the antenna input impedance will be decreased.

When the dimensions L_1 , L_2 and D_2 are maintained constant while the diameter D_1 of outer cylinder 10 is reduced, the antenna resonates at

a slightly higher frequency while the antenna input impedance is increased. A decrease of diameter D_2 , that is, the diameter of inner cylinder 11 causes a reduction of the resonant frequency of the antenna as well as of the antenna input impedance provided that L_1 , L_2 and D_1 are kept constant.

By suitably choosing the ratios of the lengths L_1 , L_2 and of the diameters D_1 , D_2 , the antenna input impedance may be adjusted to match the impedance of the coaxial transmission line which feeds the antenna. Accordingly, an impedance matching network is not required between the feeder line and the antenna. The dimensions of the antenna of the invention suitable for operation on a frequency of approximately 160 megacycles and having an antenna input impedance of 50 ohms are as follows:

	Inches	Inches
20 L_1	8	3
20 L_2	$3\frac{1}{8}$	1

For providing an antenna which will resonate at a frequency different from 160 megacycles and which will have the same antenna input impedance of 50 ohms, the above dimensions may be multiplied by the ratio of the desired frequency to the given frequency of 160 megacycles.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. An antenna comprising a coaxial transmission line having an inner conductor and an outer conductor, a cylindrical member surrounding a portion of said outer conductor, a connecting element for electrically and mechanically connecting one extremity of said member to said outer conductor, means for connecting the other end of said member to said inner conductor, and a metallic surface electrically connected to said outer conductor, the length of said antenna extending beyond said surface being electrically equivalent to one quarter of the operating wave length of said antenna.

2. An antenna comprising a coaxial transmission line having an inner conductor and an outer conductor, a cylindrical member coaxial with and surrounding the outer portion of said outer conductor, a connecting element for electrically and mechanically interconnecting the upper extremities of said member and of said outer conductor, means for connecting the free end of said inner conductor to the lowermost portion of said member, and a metallic surface electrically connected to said outer conductor, the length of said antenna extending beyond said surface being electrically equivalent to one quarter of the operating wave length of said antenna.

3. A vertical antenna comprising a coaxial transmission line having an inner conductor and an outer conductor, a cylindrical member coaxial with and surrounding the upper portion of said outer conductor, means for connecting the free end of said inner conductor to the lowermost portion of said member, and a connecting element for electrically and mechanically interconnecting the upper extremities of said member and of said outer conductor, the relative length

of said member and of the radiating portion of said outer conductor not surrounded by said member being proportioned in such a manner as to provide a predetermined input impedance of said antenna and a predetermined electrical length.

4. A vertical antenna comprising a coaxial transmission line having an inner conductor and an outer conductor, a cylindrical member coaxial with and surrounding the upper portion of said outer conductor, a connecting element for electrically and mechanically connecting the upper extremities of said member and of said outer conductor, means for connecting the lowermost portion of said member to the free end of said inner conductor, and a surface electrically connected to said outer conductor, the length of said antenna beyond said surface being electrically equivalent to one quarter of the operating wave length of said antenna, the relative length of said member and of the radiating portion of said outer conductor arranged between said surface and said member being proportioned in such a manner as to provide a predetermined input impedance of said antenna and an electrical length equivalent to one quarter of said wave length.

5. A vertical quarter-wave antenna comprising a coaxial transmission line having an inner conductor and an outer conductor, a cylindrical member coaxial with and surrounding the upper portion of said outer conductor, means for connecting the free end of said inner conductor to the lowermost portion of said member, and a connecting element for electrically and mechanically interconnecting the upper extremities of said member and of said outer conductor, the diameter of said member and of said outer conductor being such as to provide a predetermined

input impedance of said antenna and a predetermined electrical length.

6. A vertical antenna comprising a coaxial transmission line having an inner conductor and an outer conductor, a cylindrical member coaxial with and surrounding the upper portion of said outer conductor, a connecting element for electrically and mechanically connecting the upper extremities of said member and of said outer conductor, means for connecting the lowermost portion of said member to the free end of said inner conductor, and a surface electrically connected to said outer conductor, the length of said antenna beyond said surface being electrically equivalent to one quarter of the operating wave length of said antenna, the diameter of said member and of said outer conductor being such as to provide a predetermined input impedance of said antenna and an electrical length equivalent to one quarter of said wave length.
